COMBINED TWIN BED AND TABLE UNIT

Chester A. Pink, Highland Park, Ill., assignor to The Englander Company, Inc., Chicago, Ill., a corporation of Delaware

Filed Sept. 8, 1959, Ser. No. 57,471

Term of patent 14 years

(Cl. D5—4)

Fig. 1.

Fig. 2.

FIG. 1 is a perspective view of a combined twin bed and table unit embodying my design; and

FIG. 2 is another perspective view showing the unit in open position.

The dominant features of my design reside in those portions shown in full lines on the drawing, and the back of the unit is conventional.

I claim:

The ornamental design for a combined twin bed and table unit, substantially as shown and described.
